UNITED STATES PATENT OFFICE.

GEORGE E. BROWER AND ERNEST C. BROWER, OF BROOKLYN, NEW YORK.

GARMENT-PRESS AND CASE.

SPECIFICATION forming part of Letters Patent No. 676,458, dated June 18, 1901.

Application filed December 2, 1898. Serial No. 698,069. (No model.)

To all whom it may concern:

Be it known that we, GEORGE E. BROWER and ERNEST C. BROWER, citizens of the United States, residing in the borough of Brooklyn, 5 city of New York, county of Kings, and State of New York, have invented certain new and useful Improvements in Garment-Presses and Cases for the Same, of which the following is a specification, reference being had to the accompanying drawings, forming a part of the same, wherein—

Figure 1 represents a perspective view of the case open, showing the pressure device and garment books or covers in position; Fig. 15 2, a perspective of a trousers book or cover, and Fig. 3 a preferred construction of pressure device.

Referring to the drawings, *a* represents a case, preferably of wood, provided with a 20 cover *a'* and a drop-front *a''*.

b represents the garment books or covers in this instance as adapted to trousers. These books are designed to hold the garment stretched to its full length.

25 *c* represents a board adapted to fit into the case and is provided with springs *c' c''*, &c., that bear upon the cover when closed and create a pressure upon the books or covers.

The books or covers are preferably made of

pastebord covered with linen and may be 30 shaped to suit each particular garment, the idea being to provide each separate garment with a separate book or cover before submitting the same to pressure.

The operation is as follows: The garment 35 is properly folded and placed flat in one of the books. The book is then closed and slid or placed in the box and the spring-pressed board placed upon the top of the same and the box closed.

Having now described our invention, what we claim, and desire to secure by Letters Patent, is—

A garment-press and case consisting of a box provided with a hinged cover and a hinged 45 drop side in combination with a spring-pressed board and a series of books for containing the garments, the said garments being held under compression by said spring-pressed board acting in conjunction with the 50 cover, by the books in series and by the bottom of the box, substantially as set forth.

GEORGE E. BROWER.
ERNEST C. BROWER.
